DUMP CAR

William L. Burner, Columbus, Ohio, assignor to
 Western Wheeled Scraper Company, Aurora,
 Ill., a corporation of Illinois

Application March 3, 1930. Serial No. 432,783

28 Claims. (Cl. 105—276)

The present invention relates to dump cars, having particular, though not essential, application to dump cars of the general type wherein the tilting bed of the car is adapted to dump to either side of the car and wherein the side doors are mounted on the bed to swing outwardly and downwardly on the dumping side to a position approximately parallel with the bottom or floor of the bed to form a lateral extension thereof, such serving as a chute for directing the load out away from the car.

More particularly, the invention is concerned with the mechanism for controlling the movement of these side doors. One of the general objects of the invention is to provide improvements in this door controlling mechanism which will permit interruption of the downwardly swinging motion of the door on the dumping side without injury to the door controlling mechanism or door, or without interfering with the continued tilting of the bed. Thus, if in the dumping operation, this door on the dumping side should strike a previously dumped pile of material or should strike any other obstruction which would prevent the full normal lowering movement of the door, the door can stop at this point without injury to itself or to its controlling mechanism, and without interfering with the full range of tilting movement of the bed.

A further object of the invention is to provide improved door controlling mechanism wherein the instrumentalities for controlling each door are normally disposed to the same side of the longitudinal medial center line of the car as the door controlled thereby. The present embodiments of door controlling mechanism are particularly adapted to cars wherein the bed is tilted to dumping position about fulcrum supports spaced laterally from this longitudinal medial center line of the car, although this particular arrangement of the pivotal supports of the bed is not essential.

Other objects of the invention will appear from the following detailed description thereof. In the accompanying drawings illustrating certain preferred embodiments of the invention:

Figure 1 is an end elevational view of the car with the bed upright and the doors closed, parts being broken away in section;

Figure 2 is a similar fragmentary view, illustrating in dotted lines and in full lines two positions of the bed in its movement to dumping position;

Figure 3 is a vertical longitudinal sectional

view taken approximately on the plane of line 3—3 of Figure 1;

Figure 4 is a fragmentary end view of a modified construction, illustrating in full lines and in dotted lines the normal and tilted positions of the bed;

Figure 5 is another similar view in transverse section, illustrating another embodiment of the door controlling mechanism of my invention;

Figure 6 is a similar sectional view of still another embodiment; and

Figure 7 is a fragmentary sectional view of another embodiment somewhat similar to Figure 6.

Referring first to the construction illustrated in Figures 1, 2 and 3, the car comprises an under frame designated 10 in its entirety, a tilting bed 11, and side doors 12, 12'. The under frame 10 is of any conventional construction, usually comprising two longitudinally extending I-beams 13 having appropriate journal mounting on the car wheels 14. At different points along the length of the car there are provided bolsters or like transversely extending frame members 15 which are rigidly secured to the longitudinally extending beams 13. These transverse frame members 15 are provided with the stationary fulcrum supports about which the bed 11 tilts in the dumping operation, such fulcrum supports consisting of downwardly extending notches or recessed bearing surfaces 16, 17. The frame of the tilting bed 11 may be of any suitable construction, such frame portion being indicated at 18, and extending downwardly from this frame structure are brackets 19 which carry fulcrum pins 21, 22 at each side of the bed, adapted for cooperation with the recessed fulcrum supports 16, 17. The arrangement of these two fulcrum pins on each bracket 19 is best illustrated at the elevated right-hand side of the car in Figure 2. When the bed is in the normal transport position illustrated in Figure 1 its weight and that of its load is preferably borne upon the top surfaces of the longitudinal I-beams 13, or upon a joining plate secured thereto, the inner fulcrum pins 21 being slightly spaced from the bottoms of the inner bearing recesses 16 at this time. When the bed starts to tilt in either direction, as to the left in Figure 2, the inner fulcrum pin 21 on this side engages with the bottom of its fulcrum recess 16 in the first part of the tilting movement, and thereafter during a considerable part of such movement the bed tilts about the longitudinal axis of the pin 21. As the bed continues to tilt towards the limit of its dumping movement

85
 90
 95
 100
 105
 110

the outer fulcrum pin 22 on this side engages with the bottom of its associated fulcrum recess 17, and thereafter the load is transferred to this outer pin and the final movement of the bed is 5 around the longitudinal axis of that pin. It will be observed that by shifting the point of pivotal support outwardly in this manner during the dumping operation, the bed can be swung up to a steeper angle without the possibility of the 10 center of gravity of the bed passing beyond the vertical plane of the fulcrum support. It will be understood that if this occurred it would be necessary to exert power on the bed to restore it to normal position, and such is undesirable. The 15 depths of the bearing recesses 16 and 17 are so related to the relative heights of their respective fulcrum pivots 21 and 22 that the transposition of the fulcrum point from the inner pin to the outer pin results in the center of gravity of the 20 bed being lowered. Such lowering of the center of gravity during the tilting movement of the bed reduces the amount of power necessary to dump the bed. While the foregoing constitutes the preferred manner of mounting the bed for 25 dumping movement, nevertheless it will be understood that the invention can be embodied in constructions where there is only a single laterally spaced fulcrum at each side of the car, or where the bed is mounted to tilt in any other 30 manner.

It will be understood that these fulcrum pins 21, 22 and bearing sockets 16, 17 are located at a plurality of points along the length of the car.

Any conventional arrangement of air cylinders, mounted on the car, may be employed for tilting the bed, or the latter may be tilted by a suitable device disposed alongside the truck, both types of mechanisms being old and well known.

The doors 12, 12' have downwardly extending 40 pivot lugs 24 at their lower edges which have hinge mounting on pivot pins 25 carried by brackets extending outwardly from the frame 18 of the bed. At each end of the bed a bar or arm 26 is secured to the end of the door and extends 45 inwardly therefrom. The door controlling mechanisms are disposed at the ends of the bed to act on these arms, and inasmuch as the instrumentalities employed to control each door are duplicates on opposite sides of the car I shall describe only one of these mechanisms. At the 50 inner end of the arm 26 is mounted a pivot pin 27, to which a link 28 is pivotally connected. This link is preferably adjustable in length, as by constructing the inner section thereof with a 55 threaded outer end and by constructing the outer section in the form of an internally threaded sleeve 29 adapted to screw over the inner section, this outer sleeve portion 29 being formed with the eye which receives the pivot 27. By removing 60 this pivot the sleeve section 29 can be screwed inwardly or outwardly to adjust the effective length of the link 28. The inner end of said link is pivotally connected at 31 to the lower arm of a lever 32 which is pivotally mounted intermediate 65 its ends on a pivot stud 33 supported on the end of the bed 11. The upper arm of said lever has an offset portion 34 which carries a pivot pin 35 to which one end of a link 36 is connected.

The other end of said link is pivotally connected at 37 to a curved rider member 38. The lower end of this rider member is pivotally mounted at 39 on a bracket 41 depending from the underside of the bed frame 18. In the arrangement illustrated the pivot 39 is located substantially coaxially of the inner fulcrum pin 21, be-

ing spaced endwise therefrom; this, however, is not essential as the pivot 39 may be located at different points so long as the inner curved surface of the rider member 38 will have proper coaction with its associated roller 42 in the tilting movement of the bed.

There are two of these rollers 42, one for each of the two opposite rider members 38, these two rollers being coaxially mounted on a pivot 43 disposed substantially in the vertical medial plane of the car. Referring to Figure 3, these rollers are mounted between inner and outer plate portions 44 forming the inner and outer sides of a U-shaped bracket which is fixedly secured to the tops of the sill beams 13, the ends of the pivot pin 43 being mounted in these plate portions. The upper edges of these plate portions extend above the rollers 42, 42', thereby forming the sides of a channel shaped guideway, the bottom of which is defined by the rollers 42, 42'. The rider members 38 move in this guideway in the tilting of the bed, with their curved inner surfaces bearing against the rollers. It is preferable, although not necessary, to provide an individual roller for each of the two rider members 38, 38', because when the bed is being tilted, as to the left in Figure 2, the right-hand rider member 38' has considerable rolling movement on its roller whereas the left-hand rider member 38 has little if any rolling movement on its 105 roller, and, conversely, when the bed is tilted in the other direction the opposite is true.

Any suitable arrangement may be employed for preventing each rider member from engaging with the other roller, as, for example, by the 110 provision of a suitable dividing partition between the rollers. Another arrangement, which I have shown in the present construction, is to provide a groove 45 on the inner side of the member 38, running throughout the length of its curved inner 115 surface, with this groove disposed in the plane of the opposite roller, and forming a like groove 45' in the other rider member 38', but along the opposite side of this curved inner surface, and with this groove lying in the plane of the roller 120 engaged by the opposite rider member 38. These curved inner surfaces of the rider members are arcs which are preferably substantially concentric with the inner fulcrum pivot 21 on the opposite side of the car.

Stop means are provided for limiting the downward folding movement of the door on the dumping side, so that the motion of such door will be stopped, relatively to the bed, when the door is extending substantially parallel with the bed to 130 serve as a chute at the side thereof, see Figure 2. Such stop means may be in the form of an extension on the door projecting below the hinge line and adapted to engage the frame of the bed, or such stop means may be arranged to coact with 135 the link mechanism controlling the door. The latter arrangement is shown, and comprises a stop bracket 47 secured to the end of the bed at each side thereof and adapted to be engaged by a cooperating stop shoulder 48 projecting from the inner or rear side of the motion reversing lever 32. These stops come into engagement with each other when the dumping door is extending as a substantially parallel prolongation of the bottom of the bed, as shown in Figure 2, preventing further downward pivotal movement of the door relatively to the bed. In addition, these stops prevent the pivot pins 31 from moving into a dead center or past center locking relation with respect to the pivots 27 and 33. Each motion 150

- reversing lever 32 is preferably constructed of two duplicate plates or bars secured together in spaced relation. The outer link 28 is mounted on the pivot pin 31 between these two sections, 5 and, likewise, the upper end of the inner link 36 is also mounted on the pivot pin 35 between such sections, as shown in Figure 3. The stop shoulder 48, carried by said lever, is secured to the inner or rear bar section of the lever.
- 10 With reference to the operation of the door controlling mechanism, it should be particularly noted that the weight of the load pressing against the doors and tending to swing the same outwardly establishes a force which is reversed 15 through the motion reversing levers 32 to create an inwardly acting pressure causing the arcuate rider to press inwardly against its companion roller 42 or 42'. Referring to Figure 2, as the bed starts to tilt downwardly towards the left the 20 weight of the bed and its load is first transposed to the inner line of fulcrum pivots 21 as these pivots engage the bottoms of the recesses 16. The bed continues to tilt about these inner fulcrum pivots until it reaches approximately the position 25 illustrated in dotted lines in Figure 2. During this movement, the rider member 38' on the elevating side of the bed is rolling along its roller 42' through a path substantially concentric with its curved inner surface, such member thereby 30 maintaining the door on the rising side of the bed closed. The other rider member 38 remains in approximately the same relation to its roller 42, but the downward swing of the lever pivot 33 with the tilting movement of the bed allows the 35 motion reversing lever 32 at this side to swing in a clockwise direction progressively as the bed tilts downwardly.
- Hence the door 12 at this side is permitted to open, it being noted that such opening movement follows entirely from the action of gravity 40 on the door and the pressure of the load thereagainst, this downwardly swinging movement of the door being continuously controlled in the descending direction through the action of the 45 levers 32 transmitting the door opening force as a pressure to the rider member 38. When the bed passes beyond the dotted line position illustrated in Figure 2 the remainder of the tilting movement is transposed to the outer line of fulcrum pivots 22 around which the bed continues 50 to tilt until it reaches its maximum angle. It is during this last part of the tilting movement that the main dumping operation occurs, at which time the pressure of the load is relieved 55 from the door on the rising side and such door tends to remain closed under its own weight. Hence, it is permissible to have the other rider member 38', controlling this door, leave its roller 42' during such latter part of the tilting movement because there is no tendency for the upper 60 door to open. When the bed reaches its maximum angle of tilt the lever 32 on the dumping side brings its stop 48 up against the fixed stop 47 on the bed, thereby interrupting further pivotal movement of the dumping door and holding 65 said door substantially in parallelism with the bottom of the bed, as illustrated in Figure 2. It will be observed that, if at any point in the tilting movement of the bed, the door at the dumping side should strike a pile of material or any other obstruction which would prevent its opening, the door is free to remain at this angle or position while the bed continues to tilt, even up to the point where the door is closed against the 70 side of the bed. Such follows by reason of the 75 ability of the rider member 38 to be withdrawn out of contact with roller 42.
- When the bed is tilted back to its normal position the lever pivot 33 swings in an arc toward the roller 42, thereby creating a compression thrust in the inner or upper link 36 and revolving said lever in a counter-clockwise direction to force the opened door upwardly and to closed position against the side of the bed. The rider member 38' on the other side of the bed resumes its pressure relation against its roller 42' for maintaining the other door positively closed. It will be evident that a tilting of the bed in the opposite direction merely results in a reversal of these door controlling operations.
- In Figure 4 I have illustrated a modified construction using this same general relation of rider members bearing on the centrally disposed rollers, but in this embodiment the controlling connection with the door is established below the pivot or hinge line of the door. These rider or pressure members 38, 38' have their inner faces similarly curved on arcs substantially concentric with the axes of the opposite inner fulcrum pins 21, and such members bear on their respective 100 rollers in substantially the same relation as described of the preceding embodiment. The pivots 39 upon which said members are mounted are shown as being disposed inwardly from these inner fulcrum pivots, which may also be true of the above described embodiment. In this instance these pressure members are constructed substantially in the form of bell-crank levers having outwardly extending arms 51. These arms carry pivots 52 to which links, similar to the previously described links 28, are pivotally connected. Said links have the same relation of inner threaded sections screwing into outer sleeve sections 29, for the purpose of adjusting the effective lengths of such links.
- The outer end of the sleeve section 29 is pivotally connected at 55 to an arm 56 extending downwardly from the door, below the hinge axis 25. As described of the preceding embodiment, there is a pair of these rider or pressure members at 105 the opposite end of the bed connected through a similar link arrangement with depending arms at the opposite ends of the doors. It will be noted that in this embodiment the load pressure and the weight of the door tending to swing the door 110 outwardly also establishes a pressure in the associated rider member 38, 38' tending to hold such rider member pressed against its respective roller.
- As the bed is being tilted to dumping position, 115 such pressure member on the rising side rides along this roller through almost the entire range of tilting movement for holding its door closed. At the dumping side, the hinge axis 25 of the door swings downwardly and away from the pivot 120 center 52, thereby allowing the lower door controlling pivot 55 to swing inwardly and upwardly relatively to the bed. Hence, the door at this side swings downwardly progressively with the 125 tilting of the bed, its downfolding movement being controlled through the entire tilting operation. At the completion of the tilting movement the door is held substantially parallel with the bottom of the bed, any tendency of the door to 130 continue downward movement beyond this position being resisted by the inability of the link 28 to move upwardly to any higher point because of the pressure engagement which the rider member 38 has at this time with its respective roller.

If, at any time throughout the entire range of tilting movement, the door should strike an obstruction, it can remain in that position while the bed continues to tilt, even up to the point of 5 having the door closed against the side of the car, any such interrupted movement of the door merely causing the associated rider member 38 to be swung away from its respective roller. When the bed is swung back to normal position the thrust 10 established in the link 28 swings the door back up against the bed and holds it there in locked condition. By making the links 28 adjustable in length, in this and in the previously described embodiment, any wear of the parts, springing of 15 the door, or other condition arising which might prevent the door from being completely closed, can be compensated for by adjusting these links to a different length; and, similarly, if the door is closed too forcibly or under an excessive pressure 20 such can also be corrected by reversely adjusting these links.

In some instances, as when handling wet and sticky materials, it may be desirable to give the door on the rising side a slight opening movement substantially at the beginning of the dumping operation so as to release the material tending to adhere to this door and to this side of the bed. Such action can be obtained in either of 25 the previously described embodiments by having the inner surfaces of the rider members 38, 38' curved on an arc which is not concentric with the opposite fulcrum pin 21 but which is concentric with some other point, such as a center slightly below such fulcrum pin 21. By this 30 arrangement, as the bed tilts, the rider member on the rising side of the bed is permitted to pivot or swing slightly toward its respective roller, thereby permitting its controlled door to swing outwardly through a slight movement near or 35 through the beginning of the dumping operation so as to release the material at the rising side.

In each of the above described embodiments, it will of course be understood that the tilting of the bed may occur solely about the fulcrum 40 trunnions 21 and that the second set of trunnions 22 may be omitted.

In Figure 5 I have illustrated an embodiment wherein the door controlling mechanism is disposed below the bed, the latter having tilting 45 movement about laterally spaced fulcrums substantially as described of the preceding embodiments. Each door controlling mechanism comprises an inner link 61 and an outer link 62, pivotally connected together at 63. The inner 50 end of the inner link is pivotally connected at 64 to a bracket 65 which is secured to the under-frame on the same side thereof as the door controlled by said mechanism. The outer end of the outer link 62 is pivotally connected at 66 to 55 an arm 56 extending downwardly from the door, below the hinge axis thereof. The outer link 62 is constructed of two sections having a one-way or lost motion operating connection therebetween which permits the effective length of 60 said link to lengthen on the rising side of the bed. The two sections consist of the outer section 67 and the inner section 68, the pivot eye for receiving the pivot 63 being formed in this 65 inner section. A rod 69 is rigidly secured to the inner section 68 and extends along one side of the outer link section 67, having sliding engagement in two spaced apertured guides 71 and 72 projecting laterally from the outer link section 67. When the bed is in its normal position, as 70 illustrated in full lines, the adjacent ends of 75

these two link sections abut each other, at this time forming a rigid link structure capable of resisting compression stresses for holding its respective door closed.

When the bed tilts to dumping position, as illustrated in dotted lines, the outer link section 67 on the rising side is free to slide outwardly along the guide rod 69 of the inner section, thereby permitting the link to lengthen for accommodating such movement of the bed.

The movement of the pivot joint 63 may, if desired, be guided on the dumping side of the bed by a guide track 73 secured to the underside of the bed and disposed above each link assembly. For cooperating with this track, a guide roller 74 may be mounted on the pivot pin 63. The track preferably slopes inwardly and downwardly toward the center of the bed and has a downwardly curved end, as shown.

As the bed starts to tilt to dumping position the door on the rising side is maintained substantially closed until the pressure of the load is removed therefrom and the bed has tilted to an angle where the weight of the door tends to retain it in closed position, the two sections 67 and 68 of the outer link having no appreciable separating movement until after this point has been passed.

On the dumping side the pivot 66 is permitted to swing inwardly and upwardly relatively to the frame of the bed, the roller 74 traveling inwardly along its track 73 progressively with the tilting of the bed and controlling its door so that it is lowered gradually, without any sudden dropping. In the final dumping position the arm 56 engages the underside of the bed frame and holds the door extending substantially parallel with the bottom of the bed. If the descending door should strike an obstruction it can stop and remain in that position, the outer section 67 of the outer link then sliding outwardly along the guide rod 69 with the continued tilting of the bed.

It will be understood that there will be a plurality of these door controlling mechanisms located at different points along the length of the car; and, if desired, this type of door controlling mechanism may be employed in conjunction with either of the previously described embodiments, such embodiments operating at the ends of the bed and the construction shown in Figure 5 being disposed at intermediate points along the car, underneath the bed.

In the construction shown in Figure 6, the bed tilts about the laterally spaced fulcrums 21, and the door controlling mechanism comprises extensible links 77 also having a one-way or lost motion operating relation permitting the descending door on the dumping side of the car to have its movement interrupted independently of the continued tilting of the bed. Each of these links comprises an inner section 78 and an outer section 79 which have relative sliding movement by forming the inner section with a reduced guide extension 81, the outer section 79 being constructed in the form of a sleeve adapted to have relative telescopic movement over the reduced outer portion 81. The inner section 78 is pivotally connected with the underframe on a pivot 82 supported on a bracket 83, and the outer section 79 is pivotally connected at 84 with an extension of the door depending below the hinge axis thereof. When the bed is in its normal, righted position, the two sections of each door controlling link are at the inner limit of their relative telescopic movement, with the shoulders 86 abutting, such links then

145

150

functioning as rigid compression struts for holding the doors closed against the pressure of the load and their own weight. As the bed starts to tilt the link 77 on the rising side is permitted to extend in length by virtue of such telescopic connection, but there is no appreciable extension thereof until after the pressure of the load is removed from the rising door, so that the door is retained substantially closed by the link 77 until 10 after the bed has tilted to a point where the door will remain closed under its own weight. On the dumping side, the door swings down gradually with the tilting movement of the bed, the link 77 on this side functioning as a stiff compression member for controlling the entire movement of the door. When the bed reaches the maximum tilting angle this door is held substantially parallel with the bed either through the link 77 or through separate stop means. If the descending door should strike an obstruction, it can remain in that position, the link 77 merely extending in length with the continued tilting of the bed.

In Figure 7 I have shown a construction similar 25 to Figure 6 except that each door controlling link 77' has its inner point of pivotal connection 82 with the under frame located on the same side of the longitudinal medial plane of the car as the door controlled by said link. Each link 30 comprises the inner section 78' and the outer section 79', with the inner section constructed with a reduced portion 81' sliding in the sleeve formation of the outer portion 79'. In this embodiment, the trunnion pins 21' are mounted in bearing recesses 16' which are widened slightly transversely of the inner frame so as to permit the trunnion pin at the dumping side to roll or slide inwardly slightly in the dumping operation. This compensates for the fact that on the rising side of 40 the bed, the link 77' swings through an arc of shorter radius than the arc which would normally be inscribed about the opposite fulcrum pin 21'. The door on the rising side is positively held closed during the tilting movement, and the 45 descending door on the lowering side is free to move or to be stopped during the continued tilting of the bed, this permissive opening of the dumping door following from the lost motion or one-way operating relation of the telescopic link 50 sections 78' and 79'. In the righting of the bed the compression force established in the link 77' on the dumping side shifts the bed back to its normal position with the fulcrum pins 21' disposed at the outer ends of their slotted bearing 55 recesses 16'. If desired, the bottom of each slotted bearing recess 16' may be sloped upwardly at a slight angle towards its inner end and each fulcrum pin 21' may comprise a roller for 60 rolling along said bottom surface, whereby the weight of the bed will tend to roll the fulcrum roller at the dumping side back towards the outer end of said sloping bearing recess. These bearing recesses may be made narrow, as shown 65 in Figs. 1 to 6, without provision for lateral shifting of the fulcrums 21', by arranging each door 12, 12' so that the ends thereof fit between the ends of the bed, or so that each door does not in itself close against the ends of the bed, but has a 70 guard plate thereon at each end adapted to extend in overlapping relation on the outer side of the end wall of the bed to close the slight space between the door and the end wall of the bed. In either of these constructions the door on the rising side can have a slight inward movement 75 with respect to the bed so that there is no neces-

sity of any lateral shifting of the fulcrums 21'. In all of the above embodiments it will be understood that the construction at the right hand side of the car is a duplicate of that shown of the left hand side.

While I have shown what I consider to be the preferred embodiments of my invention, nevertheless, it will be understood that such are merely exemplary and that numerous modifications and rearrangements may be made without departing from the essence of the invention.

I claim:

1. In a dump car, the combination of an under frame, a tilting bed rockable about a fulcrum axis relatively to said under frame, a side door for said bed pivotally connected therewith, and door controlling mechanism comprising a member curved substantially concentrically with said fulcrum axis carried by the bed, and means operatively connecting said member with said door.

2. In a dump car, the combination of an under frame, a tilting bed rockable about a fulcrum axis relatively to said under frame, a side door for said bed pivotally connected therewith, and door controlling mechanism comprising a member curved substantially concentrically with said fulcrum axis and pivotally mounted on said bed, a guide surface on said under frame on which said curved member has movement in the tilting of the bed, and means operatively connecting said curved member with said door.

3. In a dump car, the combination of an under frame, a tilting bed rockable selectively about fulcrums at opposite sides of said under frame, side doors for said bed pivoted thereto at each side thereof, and door controlling mechanism comprising a member curved substantially concentrically with the fulcrum at the opposite side of the car, a guide surface on the under frame along which said curved member has movement in the tilting of the bed, and means operatively connecting said curved member with one of said doors.

4. In a dump car, the combination of an under frame, a tilting bed rockable selectively about fulcrums at opposite sides of said under frame, side doors for said bed pivoted thereto at each side thereof, and door controlling mechanism for each door comprising a member mounted on the bed at the same side as the door controlled thereby, said members being curved substantially concentrically with the fulcrums at the opposite sides of the car, guide surfaces on the under frame along which said curved members have movement in the tilting of the bed, and means operatively connecting said curved members with their respective doors.

5. In a dump car, the combination of an under frame, a tilting bed rockable selectively about fulcrums at opposite sides of said under frame, side doors for said bed pivoted thereto at each side thereof, and door controlling mechanism for each door comprising a member pivotally mounted on the bed and curved substantially concentrically with the fulcrum at the opposite side of the car, guide surfaces on said under frame along which said curved members have movement in the tilting of the bed, and link mechanism connecting said curved members with their respective doors.

6. In a dump car, the combination of an under frame, a tilting bed rockable selectively about fulcrums at opposite sides of said under frame, side doors pivotally connected with said bed to swing outwardly and downwardly to dumping po-

- sition, and door controlling mechanism for each door comprising a member pivotally mounted on said bed and curved substantially concentrically with the fulcrum at the opposite side of the car, 5 guide surfaces on said under frame along which said curved members have riding movement in the tilting of the bed, and link means operatively connecting each of said curved members with its respective door whereby said members are normally held against said guide surfaces.
7. In a dump car, the combination of an under frame, a tilting bed rockable selectively about fulcrums at opposite sides of said under frame, side doors for said bed pivoted thereto at each 15 side thereof, roller means carried by said under frame substantially in the longitudinal medial plane of the car, and door controlling mechanism for each door comprising a rider member pivotally mounted on the bed and having one surface thereof curved substantially concentrically with the fulcrum at the opposite side of the car, such curved surfaces of the two rider members having riding movement on said roller means in the tilting of the bed, and link means operatively connecting each of said rider members with its 20 respective door.
8. In a dump car, the combination of an under frame, a tilting bed rockable selectively about fulcrums at opposite sides of said under frame, 30 side doors for said bed pivoted thereto at each side thereof, roller guide means carried by said under frame and disposed approximately in the longitudinal medial plane of the car, and door controlling mechanism for each door comprising 35 a rider member pivotally mounted on said bed on the same side thereof as the door controlled thereby, the inner surface of each rider member being curved substantially concentrically with the fulcrum at the opposite side of the car, the 40 curved surfaces of said two rider members having riding movement on said roller guide means in the tilting of the bed, and motion reversing link means operatively connecting said rider members with their respective doors.
- 45 9. In a dump car, the combination of an under frame, a tilting bed rockable selectively about fulcrums at opposite sides of said under frame, side doors for said bed pivoted thereto at each side thereof, guide means mounted on said under frame substantially in the longitudinal medial plane thereof, rider members pivotally mounted on the bed and having riding movement on said 50 guide means in the tilting of the bed, levers pivotally mounted on the bed, and links operatively connecting said levers with said doors and with said rider members.
- 55 10. In a dump car, the combination of an under frame, a tilting bed rockable selectively about fulcrums at opposite sides of said under frame, 60 side doors for said bed pivoted thereto at each side thereof, guide means mounted on said under frame at each end of the car and intermediate the sides thereof, arcuate members pivotally mounted on said bed at the ends thereof and 65 adapted to have riding engagement on said guide means in the tilting of the bed, levers pivotally mounted on the ends of the bed, and links operatively connecting said levers with said doors and with said arcuate members.
- 70 11. In a dump car, the combination of an under frame, a tilting bed rockable selectively about fulcrums at opposite sides of said under frame, side doors for said bed pivoted thereto at each side thereof, a guide surface on the under frame, 75 a member movably mounted on the car for controlling each door having a surface curved substantially concentrically with the fulcrum at the opposite side of the car, the curved surfaces of both of said members having movement on said guide means in the tilting of the bed in opposite directions, and means operatively connecting said curved members with their respective doors below the pivot axes of the doors.
12. In a dump car, the combination of an under frame, a tilting bed rockable selectively about fulcrums at opposite sides of said under frame, 80 side doors for said bed pivoted thereto at each side thereof, a guide surface on the under frame, and door controlling mechanism for each door comprising a member curved substantially concentrically with the fulcrum at the opposite side of the car, the curved surface of said member having movement on said guide surface in the tilting of the bed, arms extending from said curved members, and link means operatively connected between said arms and the lower portions of the doors.
13. In a dump car, the combination of an under frame, a tilting bed, rockable selectively about fulcrums at opposite sides of said under frame, 85 side doors for said bed pivoted thereto at each side thereof, and door controlling mechanism for each door comprising a member mounted on the bed on the same side of the car as the door controlled thereby, means operatively connecting each of said members with its respective door, and means on said under frame in substantially the vertical medial plane of said car with which the member at the rising side has bearing engagement during substantially the entire tilting 90 movement of the bed, said door controlling mechanism permitting the descending door on the dumping side to move or to be stopped during the tilting of the bed.
14. In a dump car, the combination of an under frame, a tilting bed rockable selectively about fulcrums at opposite sides of said under frame, side doors for said bed pivoted thereto at each side thereof, and door controlling mechanism for each door comprising arcuate members pivotally 100 mounted on the bed at the same side thereof as the door controlled thereby, means operatively connecting said arcuate members with their respective doors, guide means on said under frame with which the arcuate member at the rising 105 side of the bed has bearing engagement until the bed has tilted to the point where gravity will hold the door on the rising side closed, said door controlling mechanism permitting the descending door on the dumping side to move or to be stopped during the continued tilting of the bed.
15. In a dump car, the combination of an under frame, a tilting bed rockable selectively about fulcrums at opposite sides of said under frame, side doors for said bed pivoted thereto at each 110 side thereof, and door controlling mechanism for each door comprising pressure members movably mounted on the bed at a point below the plane of the load carrying surface of said bed and on the same side thereof as the door controlled 115 thereby, guide means mounted on the under frame, said guide means being disposed at a point above the pivotal connections of said pressure members with said bed, and means operatively connecting said doors with their respective pressure members whereby outwardly acting pressure on the doors tends to press said pressure members inwardly against said guide means.
16. In a dump car, the combination of an under frame, a tilting bed rockable selectively about ful- 120

- erums at opposite sides of said under frame, side doors for said bed pivoted thereto at each side thereof, and door controlling mechanism for each door comprising a curved door controlling member mounted on the bed and disposed entirely on the same side of the car as the door controlled thereby, means operatively connecting each of said members with its respective door, and guide means mounted on the under frame with which 5 said curved members have engagement, said guide means being disposed at a point above the pivotal connection of said controlling member with the bed.
17. In a dump car, the combination of an under frame, a tilting bed normally resting on two laterally spaced fulcrums on said under frame, side doors pivotally connected with said bed to swing outwardly and downwardly to their dumping position, door controlling mechanisms for 10 each door comprising a member curved substantially concentrically with the fulcrum at the opposite side of the car, means operatively connecting said member with said door, and means for shifting the pivotal center around which said bed 15 tilts.
18. In a dump car, the combination of an under frame, a tilting bed mounted thereon, means comprising dual pivots at each side of the car adapted to alternately support the bed on said 20 under frame during a tilting movement to either side, side doors pivotally connected with the bed to swing outwardly and downwardly to their dumping position, door controlling mechanisms for each door comprising a member curved substantially concentrically with one of the dual 25 pivots at the opposite side of the car, and means operatively connecting said member with said door.
19. In a dump car, the combination of an under frame, a tilting bed mounted thereon, means comprising inner and outer pivots at each side of the car adapted to alternately support the bed on said under frame during a tilting movement to either side, side doors pivotally connected with 30 35 said bed to swing outwardly and downwardly to their dumping position, door controlling mechanisms for each door comprising a member curved substantially concentrically with the inner pivot at the opposite side of the car, and means operatively connecting said member with said door.
20. A dump car comprising an underframe, a tilting bed mounted thereon, a side door connected with the bed to swing downwardly into open position, and mechanism for controlling the 40 45 50 operation of said door comprising a curved member pivotally mounted on said bed concentrically with the tilting axis thereof, link means connecting said curved member with said door, and a guide surface on said underframe with which the upper end of said curved member has bearing engagement in the normal transport position of said bed, and on which said member has sliding movement during a tilting movement of said bed.
21. A dump car comprising an underframe, a tilting bed mounted thereon, a side door connected with the bed to swing downwardly into open position, and mechanism for controlling the 55 60 65 operation of said door comprising a curved member pivotally mounted at one end on said bed concentrically with the tilting axis thereof, link means connected with said curved member intermediate the ends thereof and with said door, and a guide surface on said underframe with which 70 75 the upper end of said curved member has bear-
- ing engagement in the normal transport position of said bed, and on which said member has sliding movement during a tilting movement of said bed.
22. In a dump car, the combination of an underframe, a tilting bed mounted thereon, means comprising dual pivots at each side of the car adapted to alternately support the bed on said underframe during a tilting movement to either side, side doors pivotally connected with the bed to swing outwardly and downwardly to their dumping position, door controlling mechanisms for each door comprising a curved member pivotally mounted on the bed coaxially with one of the dual pivots which support said bed, and means operatively connecting said member with said door.
23. In a dump car, the combination of an underframe, a tilting bed mounted thereon, means comprising inner and outer pivots located at each side of the car and adapted to alternately support the bed on said underframe during a tilting movement to either side, side doors pivotally connected with the bed to swing outwardly and downwardly to their dumping position, door controlling mechanisms for each door comprising a curved member pivotally mounted on the bed coaxially with the inner pivot of said bed supporting means, and means operatively connecting said member with said door.
24. A dump car comprising an underframe, laterally spaced fulcrum supports stationarily disposed on said underframe adjacent to the outer sides thereof, a tilting bed supported in substantially stable equilibrium on said underframe and comprising laterally spaced fulcrums stationarily mounted on said bed and adapted to cooperate with said laterally spaced fulcrum supports, said bed being operative to dump to either side about said laterally spaced fulcrums, side gates at opposite sides of the bed hingedly connected with the bed to swing outwardly and downwardly from the side of the bed to open position in the dumping operation, and gate control mechanism for each gate operative at the dumping side to allow the gate to be opened by gravity or to permit the gate to be stopped by an obstruction during continued dumping movement of the bed and serving to positively close the gate during the righting movement, and operative at the rising side to positively hold the gate closed, each of said gate controlling mechanisms comprising a rider member pivotally mounted on the bed, motion transmitting linkage operatively associated between said rider member and its respective gate to control the opening and closing movements of said gate, and a device pivotally connected with said underframe and against which device said rider member is adapted to bear, said rider member being movable out of engagement with said device.
25. A dump car comprising an underframe, laterally spaced fulcrum supports stationarily disposed on said underframe adjacent to the outer sides thereof, a tilting bed supported in substantially stable equilibrium on said underframe and comprising laterally spaced fulcrums stationarily mounted on said bed and adapted to cooperate with said laterally spaced fulcrum supports, said bed being operative to dump to either side about said laterally spaced fulcrums, side gates at opposite sides of the bed hingedly connected with the bed to swing outwardly and downwardly from the side of the bed to open position in the dumping operation, and gate control mechanism for each gate operative at the dumping side to allow the gate to be opened by gravity or to permit the gate to be stopped by an obstruction during continued dumping movement of the bed and serving to positively close the gate during the righting movement, and operative at the rising side to positively hold the gate closed, each of said gate controlling mechanisms comprising a rider member pivotally mounted on the bed, motion transmitting linkage operatively associated between said rider member and its respective gate to control the opening and closing movements of said gate, and a device pivotally connected with said underframe and against which device said rider member is adapted to bear, said rider member being movable out of engagement with said device.

mechanism for each gate operative at the dumping side to allow the gate to be opened by gravity or to permit the gate to be stopped by an obstruction during continued dumping movement 5 of the bed and serving to positively close the gate during the righting movement, and operative at the rising side to positively hold the gate closed, each of said gate controlling mechanisms comprising a pivoted member pivotally mounted on 10 the end of the bed whereby a portion of said pivoted member can project above the plane of the load carrying surface of said bed, motion transmitting mechanism operatively associated between said pivoted member and its respective 15 gate to control the opening and closing movements of said gate, and a cooperating member connected with said underframe and against which said pivoted member is adapted to bear, said pivoted member being movable into and out 20 of engagement with said cooperating member.

26. A dump car comprising an underframe, laterally spaced fulcrum supports stationarily disposed on said underframe adjacent to the outer sides thereof, a tilting bed supported in 25 substantially stable equilibrium on said underframe and comprising laterally spaced fulcrums stationarily mounted on said bed and adapted to cooperate with said laterally spaced fulcrum supports, said bed being operative to dump to either 30 side about said laterally spaced fulcrums, side gates at opposite sides of the bed hingedly connected with the bed to swing outwardly and downwardly from the side of the bed to open position in the dumping operation, and gate control mechanism for each gate operative at the dumping side to allow the gate to be opened by 35 gravity or to permit the gate to be stopped by an obstruction during continued dumping movement of the bed and serving to positively close 40 the gate during the righting movement, and operative at the rising side to positively hold the gate closed, each of said gate control mechanisms comprising a pivoted member pivotally mounted on the bed on a pivot axis disposed intermediate 45 the longitudinal center line of the bed and the hinge axis of the gate controlled by that member, motion transmitting mechanism operatively associated between said pivoted member and its respective gate to control the opening and closing 50 movements of said gate, and a cooperating member connected with said underframe and against which said pivoted member is adapted to have rolling bearing engagement, said pivoted member being movable into and out of engagement 55 with said cooperating member.

27. A dump car comprising an underframe, laterally spaced fulcrum supports stationarily disposed on said underframe adjacent to the outer sides thereof, a tilting bed supported in 60 substantially stable equilibrium on said underframe and comprising laterally spaced fulcrums stationarily mounted on said bed and adapted to cooperate with said laterally spaced fulcrum supports, said bed being operative to dump to either 65 side about said laterally spaced fulcrums,

side gates at opposite sides of the bed hingedly connected with the bed to swing outwardly and downwardly from the side of the bed to open position in the dumping operation, and gate control mechanism for each gate operative at the dumping side to allow the gate to be opened by 80 gravity or to permit the gate to be stopped by an obstruction during continued dumping movement of the bed and serving to positively close the gate during the righting movement, and operative at the rising side to positively hold the gate closed, each of said gate controlling mechanisms comprising a lever pivotally mounted intermediate its ends on the end of the bed, said lever at the dumping side of the car moving relatively to said bed and to said underframe in the dumping operation, a link pivotally connected between one end of said lever and its respective gate, and means coacting between the other end of said lever and the underframe for controlling the position of said lever relatively to said bed at the dumping side, said latter means comprising two cooperating members arranged to have relative sliding contact and capable of relative separating motion with said members 95 out of contact with each other.

28. A dump car comprising an underframe, laterally spaced fulcrum supports stationarily disposed on said underframe adjacent to the outer sides thereof, a tilting bed supported in substantially stable equilibrium on said underframe and comprising laterally spaced fulcrums stationarily mounted on said bed and adapted to cooperate with said laterally spaced fulcrum supports, said bed being operative to dump to either 100 side about said laterally spaced fulcrums, side gates at opposite sides of the bed hingedly connected with the bed to swing outwardly and downwardly from the side of the bed to open position in the dumping operation, and gate control mechanism for each gate operative at the dumping side to allow the gate to be opened by 105 gravity or to permit the gate to be stopped by an obstruction during continued dumping movement of the bed and serving to positively close 110 the gate during the righting movement, and operative at the rising side to positively hold the gate closed, said two gate controlling mechanisms comprising two proximate contact members, one individual to each gate, both pivotally connected 115 with said underframe, and spaced from each other longitudinally of the car at one end thereof, two pivoted members at the same end of the car, one individual to each gate, both pivotally mounted on said bed on separate pivot axes, and 120 each coacting with an individual one of said contact members, each of said pivoted members being arranged for relative traveling motion along and in contact with its individual contact member, and being movable out of engagement with 125 said contact member, and motion transmitting devices operatively associated between said pivoted members and their respective gates for controlling the opening and closing of said gates.

WILLIAM L. BURNER. 140
